UNITED STATES PATENT OFFICE.

WALTER H. PERKINS, OF CHERSHIRE, CONNECTICUT, ASSIGNOR TO THE WATERBURY MFG.
CO., OF WATERBURY, CONNECTICUT, A CORPORATION.

BALL-COCK FOR FLUSHING-TANKS.

No. 909,328.

Specification of Letters Patent.

Patented Jan. 12, 1909.

Application filed July 3, 1908. Serial No. 442,088.

To all whom it may concern:

Be it known that I, WALTER H. PERKINS, a citizen of the United States, residing at Cheshire, in the county of New Haven and State of Connecticut, have invented a new and useful Improvement in Ball-Cocks for Flushing-Tanks; and I do hereby declare the following, when taken in connection with the accompanying drawings and the letters of reference marked thereon, to be a full, clear, and exact description of the same, and which said drawings constitute part of this specification, and represent, in—

Figure 1, a view partly in elevation and partly in vertical section of a ball-cock for flushing tanks constructed in accordance with my invention and shown as applied to the bottom of a flushing tank. Fig. 2 a detached view in side elevation of the shank. Fig. 3 a corresponding view of the head. Fig. 4 a view of the head in transverse section on the line *a—b* of Fig. 3.

My invention relates to an improvement in ball-cocks for flushing tanks.

Heretofore ball-cocks for flushing tanks have been made of cast-metal and have on that account been objectionable because of their cost, and because of the imperfections and porosities characteristic of cast-metal construction.

The object of this invention is to produce a ball-cock superior to such cast-metal ball-cocks in point of cheapness, lightness, simplicity, effectiveness and finish.

With these ends in view my invention consists in a wrought-metal ball-cock having certain details of construction and combinations of parts as will be hereinafter described and pointed out in the claims.

In carrying out my invention as herein shown, I form the shank 2 of the ball-cock from a single piece of wrought-metal tubing formed toward its upper end with an annular horizontal bearing-flange 3 produced by folding a portion of the metal upon itself. The lower end of the shank is formed with exterior threads 4 for the reception of a nut 5 which is brought to a bearing upon the lower face of the bottom 6 of the flushing tank, whereby the lower face of the flange 3 is brought to a bearing upon the upper face of the said bottom 6 which is formed with a circular opening 7 through which the shank is passed downward for the mounting of the cock. The upper end of the shank is formed

with exterior screw threads 8 for coaction with internal screw threads 9 formed within the body 10 of the cock, the said body 10 being also produced from a single piece of wrought-metal tubing. At its lower end the body is formed with an outwardly turned bearing-flange 11 which rests upon a washer 12 placed upon the upper face of the bearing-flange 3, the flange 11 being given a nut-like character by its provision with several faces as shown in Fig. 4 whereby it is adapted for the application to it of an ordinary wrench. At its upper end the shank 2 is contracted to form a concentric port 13 surrounded by an annular upwardly extending rib 14 forming a seat for a washer-like valve 15 secured to the lower face of a flange 16 located at the lower end of a tubular valve stem 17 having bearing in a concentric opening 18 in the inwardly turned upper end of the body 10. The stem 17 is connected at its upper end by a screw 19 with an operating-lever 20 made from a short length of tubing and mounted upon a pivot 21, in the upper end of a flat sheet-metal bracket 22 attached by any suitable means, as for instance, by screws 23, 23, to the body 10, the outer end of the lever 20 receiving one end of the lever 24 carrying the ball-float. The metal portion of the body 10 is knurled or otherwise treated to form a deep annular recess 25 the upper wall of which is pierced to form downwardly opening water ports 26 which on account of their location discharge the water downwardly into the tank instead of outwardly and upwardly.

A ball cock constructed as shown and described entirely of wrought metal is light, simple and cheap, adapted to be finished at a small cost, and being made of wrought instead of cast metal, has none of the imperfections or porosities which render cast-metal ball-cocks liable to break and to leak.

I claim:

1. In a ball-cock for flushing tanks, the combination with a wrought-metal body formed with an annular recess having discharge-openings, of a wrought-metal shank having an integral annular bearing-flange consisting of a portion of the metal folded upon itself.

2. In a ball-cock for flushing tanks, the combination with a wrought-metal body formed with an annular recess having discharge-openings, of a wrought-metal shank

having an annular bearing-flange formed by folding a portion of the metal upon itself and the said shank having its upper end contracted to form a water-port and furnished with a rib to form a valve seat.

3. In a ball-cock for flushing tanks, the combination with a wrought-metal shank, of a wrought metal body made in one piece and formed with an annular recess the upper wall 10 of which contains downwardly opening discharge-openings.

4. In a ball-cock for flushing tanks, the combination with a wrought-metal shank having an annular bearing-flange consisting 15 of a portion of the metal folded upon itself, of a body adapted to be applied to the upper

end of the said shank and having an annular recess the upper wall of which is pierced to form downwardly opening discharge-openings, a valve-stem mounted in the said head, 20 a valve carried by the said stem, an operating-lever connected with the upper end of the valve stem, and a bracket mounted upon the said head and carrying the said lever.

I testimony whereof, I have signed this 25 specification in the presence of two subscribing witnesses.

WALTER H. PERKINS.
